(57) **CLAIM**

The ornamental design for the photo booth, as shown and described.

DESCRIPTION

FIG. 1 is a front perspective view of a photo booth;

FIG. 2 is a front view of the photo booth;

FIG. 3 is a rear view of the photo booth;

FIG. 4 is a right side view of the photo booth;

FIG. 5 is a left side view of the photo booth;

FIG. 6 is a top view of the photo booth; and,

FIG. 7 is a bottom view of the photo booth.

The broken lines shown in the drawings of the photo booth illustrate the environment of the claimed design and form no part thereof.

1 Claim, 5 Drawing Sheets
